UNITED STATES PATENT OFFICE.

FRANK E. BUTTON, OF NEW YORK, N. Y.

VEHICLE-CONTROL SYSTEM.

1,307,345.

Specification of Letters Patent. Patented June 24, 1919.

Application filed May 1, 1916. Serial No. 94,533.

To all whom it may concern:

Be it known that I, FRANK E. BUTTON, a citizen of the United States, residing at the city of New York, in the borough of 5 Manhattan and State of New York, have invented certain new and useful Improvements in Vehicle-Control Systems, of which the following is a full, clear, and exact description.

This invention relates to a control system for a railway vehicle whereby, in the movement of the vehicle along the trackway, it is brought to a stop by the automatic actuation of suitable braking mechanism if the 15 operator of the vehicle fails to stop or reduce the speed of the train when traffic conditions in advance are dangerous or when approaching a portion of the trackway where the speed of the vehicle should not exceed a predetermined limit.

One of the objects of my invention is to provide a vehicle control system by means of which the critical speed, which should not be exceeded at different parts of the 25 trackway or under different traffic conditions, may be varied; or in other words to provide a multi-speed control system.

Another object of the invention is to provide a system in which the maximum speed 30 at which the vehicle may travel under "clear" traffic conditions, as well as under "dangerous" traffic conditions, is limited and the automatic train stopping mechanism will operate if either of these two limits is 35 exceeded.

Another object of the invention is to provide a cab indicator which will inform the operator of the critical or maximum speed at which the train may travel with safety 40 at different points along the trackway.

Other objects of the invention will be apparent from the detailed description hereinafter to follow and from the operation thereof, which will be particularly pointed 45 out.

In the drawing, the figure represents 50 diagrammatically one embodiment of a vehicle control system embodying the features of my invention.

In the system shown, the trackway is divided into blocks which are designated *a*, *b* and *c*, the track rails being properly insulated to form the blocks as is the usual practice. Each block is equipped with the 55 usual closed track circuit consisting of a battery 1 and a track relay 2, the track re-

lay being energized when the block is unoccupied, as is shown by the track relay 2 for the block *c*. Arranged along one side of the track rails are a plurality of ramps 60 5, 6 and 7, the ramps 6 and 7 being arranged side by side in advance of a block entrance a distance sufficient to permit the brakes to stop the car or train before it enters the block, while the ramp 5 is arranged at a 65 distance to the rear of the two ramps 6 and 7 to permit the speed of a train to be reduced by the operator to a determined speed before the vehicle passes over these ramps. Arranged adjacent each set of ramps is a 70 contact rail, which rails have been designated 8 and 9, and it is obvious that these contact rails and ramps, while shown separately in the present diagrammatic drawing, may constitute a single part.

The contact rails 8 and 9 are connected together by a wire 10, while the contact rail 9 is connected to a feeder 11 through the armature 12 of a track relay 2, the circuit from the feeder 11 passing through wire 13, 80 armature 12, contact 14, wire 15, resistance 16 to the contact rail 9. The resistance 16 is different for different blocks so that the strength of current which energizes the contact rails 8 and 9 is varied accordingly, 85 which is an important feature of the invention and its purpose will be clearly brought out in the operation of the system.

Referring now to the parts carried in the cab of the engine or other vehicle, the mechanism for applying the brakes is not shown, but the air brake valve is shown and designated 17. This air brake valve 17 is actuated by a weighted lever 18 which is held in position by a trip lever 18', which is set 95 by hand and held in engagement with the weighted lever by a spring 20. The tripping device for the trip lever comprises a solenoid 19 hereinafter referred to as the air brake solenoid which is provided with a weighted core 19'. When the solenoid is energized this core is raised out of engagement with the trip lever but upon deenergization of the solenoid, it drops and forces the trip lever out of engagement with the weighted lever 100 19' permitting the latter to fall and actuate the air brake valve.

The air brake solenoid 19 is normally energized by a closed circuit upon the vehicle which starts at battery 21 and passes 110 by means of wires 22, 22' to the solenoid 19, then through wire 23 to a pivoted arm 24

of conductive material, through the arm 24 to a similar arm 25, then by means of wires 26 and 26^a back to the battery. This circuit remains closed so long as the arms 24 and 25 are in engagement with each other, but upon disengagement of the arms, the circuit will be broken and the air brakes automatically applied. The arm 25 is pivotally mounted as at 27 and its up and down movement is controlled by the speed of the vehicle by means of a governor 28 mounted upon a shaft 28' which is driven through gearing 29. The governor 28 is of the usual ball type and moves a sleeve 30 upwardly and downwardly upon the shaft 28'. This sleeve 30 passes through an elongated slot or opening in the arm 25, and is provided with a collar or flange 31 at its lower end which is adapted to engage the arm 25 to move it upwardly against the tension of a spring 33. The aperture through which the sleeve 30 passes in the arm 25 is preferably provided with an insulating bushing 34 to prevent these parts from being electrically connected together.

The arm 24 is pivotally mounted upon a shaft 35 and has a hub 36 surrounding its pivotal point. A portion of the periphery of this hub is serrated to provide teeth 37 with which a detent lever 38 is adapted to engage, the lever being pulled into engagement with the teeth by a spring 39 so that if the free end of the arm 24 is moved upwardly, the detent lever 38 will ride over the teeth 37 and hold the free end in its uppermost position until the detent lever 38 is moved out of engagement with the teeth 37, at which time the arm 24 will move downwardly under its own weight. The engagement of the detent lever 38 with the teeth 37 is controlled by means of a trip arm 40, which is pivoted upon a shaft 41 in a position to strike the ramp 7, as the car passes over it, the engagement of the trip arm 40 with the ramp 7 moving the free end of the arm 40 toward the right as viewed in the figure and causing the curved upper end of the arm to engage a projection upon the detent lever 38 to move the latter out of engagement with the teeth 37. After the trip arm passes over the ramp 7, it is returned to its normal position by centralizing springs 42.

An arm 43 is mounted co-axially with the arm 24 upon the shaft 35, which arm is of a similar construction and has teeth 44 upon the periphery of its hub which are engaged by a detent lever 45 which is controlled by a trip arm 46 adapted to engage the ramps 5 and 6 along the trackway. The position of the arm 43 is controlled by a speed limit device which consists of a solenoid 48 actuating a core 49 to which is attached at its lower end a rod 50. The movement of the core 49 is regulated by an adjustable

spring 51, one end of which bears against a stationary guide 53 for the stem rod 50, and the other end against a washer which may be adjusted by a nut 55 threaded upon the lower end of the stem rod 50. The strength of the solenoid 48 and the spring 51 are adjusted with respect to each other so that the upward movement of the rod 50 will be proportional to the strength of current passing through the solenoid, such devices being common in different forms of electric regulators.

The core 49 controls the position of the arm 43 since the core 49 passes through an elongated aperture or opening in the same, and is provided with a collar or enlargement 56, which engages the arm 43 to move upwardly therewith. The core 49 is preferably insulated from the arm 43 by means of a bushing 57 of insulating material fitted into the slot in the arm 43. The core 49 also passes through an opening in the arm 24 and the latter is provided with a lip or extension 58 at its free end, which, when the arm 24 is permitted to fall upon throwing out the detent lever 38, engages the arm 43. The arm 43 is provided with a layer of insulating material at the point at which the extension 58 engages this arm to prevent the electrical connection of these parts. Connected to the free end of the arm 43 is a contact blade 60 which engages any one of a plurality of contacts 62 which are connected in parallel with a sectional resistance 63 so that by the movement of the contact blade along the contacts, the resistance will be gradually cut into and out of circuit. This resistance is in series with a cab indicator 65 in a circuit which starts from battery 21 and passes through wire 26^a, wire 67 to the cab indicator 65 and then through wire 68 to arm 43, contact blade 60 through all or a part of the resistance 63 depending upon the position of the arm, through wires 69 and 22 back to the battery 21. The cab indicator 65 is constructed similarly to the ordinary type of voltmeter so that the strength of current passing therethrough will cause its pointer or needle 70 to take a position corresponding to the strength of that current, the scale upon which the pointer reads being calibrated in miles per hour.

The coil 48 of the speed regulator is controlled by a circuit comprising a contact shoe 71 which is connected by a wire 72 to the coil 48 and thence by a wire 73 to the ground; the contact shoe 71 being adapted to engage with the contact rails 8, 9, etc., as the car passes over the same.

The operation of the system will now be described. Assuming that the parts are in the position shown; that is, with the cab indicator indicating a maximum speed of 35 miles per hour at which speed the train is 130

running and the train is approaching the block *c* which is clear of other trains, but due to a curve in the block the maximum speed at which the train may be run in this block even under clear traffic conditions, is 25 miles an hour. As the vehicle or car approaches the block, the contact shoe 71 will engage the contact rail 8 and since as before described, the contact rail 8 is energized from the feeder 11 through the relay armature 12 and resistance 16, the engagement of the contact shoe with this contact rail will cause an energization of the coil 48. The resistance 16 for block *c* is so adjusted that the strength of current which passes through the coil 48 of the speed limit device, will pull the core 49 to a position corresponding to 25 miles per hour. When therefore the trip arm 46 engages the ramp 5 and throws the detent arm 43 out of engagement with the teeth 44, the arm 43 will fall until it is engaged by collar 56. The contact rail 8 is longer than the ramp 5 and the shoe 71 therefore remains in engagement with the contact rail 8 after the trip arm has passed out of engagement with the ramp which will permit the detent 45 to again engage the arm 43 and hold it in a position corresponding to the determined speed, which in the example taken is 25 miles per hour. After the shoe 71 passes out of engagement with the contact rail 8, the core 49 drops to its normal position. The position of the arm 43 controls the cab indicator 65, the circuit passing through a portion of the resistance 63 and contact arm 60, as before described, and the strength of the current passing through the indicator will move the pointer to a position corresponding to 25 miles per hour.

The engineer is therefore informed of the speed to which he must reduce the speed of the train before entering the block *c* or before passing the contact rail 9 and the ramps 6 and 7. Let us assume upon reaching the contact rail 9 and the ramps 6 and 7 that the speed of the train has been reduced to the required speed, when the car or train passes over the contact rail 9, the contact shoe 71 will engage the contact rail 9 to energize the coil 48 of the speed limit device as before, but since the resistance 16 is in series with both the contact rails 8 and 9, and since the drop in potential between the contacts 8 and 9 is negligible, the strength of current which passes through the coil 48 is practically the same as passed through it when the car or train ran over the contact rail 8. The position to which the core 49 is drawn is therefore practically the same as before, so that the position of the arm 43 will remain unchanged when the trip arm 46 engages the ramp 6 to throw the detent 45 out of engagement with the teeth 44, since the collar 56 will then be in a position to support the arm 43. The trip arm 40 is also actuated by its engagement with the ramp 7 and will engage the detent 38 to throw it out of engagement with the teeth 37 of the arm 24 permitting this arm to drop until stopped by the engagement of the extension 58 with the arm 43. However, since the speed of the train has been reduced to the required speed, the governor 28 will have moved the sleeve 30 downwardly a sufficient distance to bring the collar 31 sufficiently below the arm 25 to permit this arm to follow and remain in engagement with the arm 24, so that the closed circuit through the air brake solenoid 19 will not be interrupted to cause an actuation of the air brakes.

If, however, the speed of the train has not been reduced to the required speed, the collar 31 controlled by the governor will prevent the arm 25 from remaining in engagement with the arm 24 as it drops and therefore the circuit controlling the air brake mechanism will be broken and the brakes will be applied.

Assuming that the speed of the train has been reduced to the required speed, the train then enters block *c* and will pass through the block under the control of the motorman until the set of contact rails and ramps are reached for the next block.

It will be seen that upon reaching the next set of contact rails and ramps, the strength of current passing through the contact rail may be regulated by providing the proper resistance between the contact rails and the feeder so that the determined speed at which the vehicle must pass through the next block may be increased to, say, forty miles per hour, or may be reduced to, say, fifteen miles per hour, even though there is no train in the next block.

Assuming now that the train is approaching the block *c* and this block is occupied by another train, the presence of the train will deenergize the track relay 2, which will cause the armature 12 of the track relay to break the circuit which energizes the contact rails 8 and 9. Assuming now that a train is approaching block *c* under these conditions, when the contact shoe 71 engages the contact rail 8, the coil 48 of the speed limit device will not be energized and the arm 43 will, when the trip arm 46 is actuated, fall to its lowermost position, which may correspond to a speed of, say, five miles per hour at which speed the train is in absolute control of the engineer. In this position the contact arm 60 will cut in the entire resistance 63 so that the weakest current passes through the cab indicator 65 and the needle of the cab indicator will therefore be set for its smallest reading which will correspond to, say, five miles per hour. This informs the engineer at once that the block *c* is occupied and that he should enter the next block at a speed of not greater than 130

- five miles per hour. If the speed of the train is brought within this limit before reaching the contact rail 9 and the ramps 6 and 7, the governor 28 will have moved the sleeve 30 downwardly a sufficient distance to bring the collar 31 to a position in which it will permit the arm 25 to follow the arm 24 when the same is released by the engagement of the trip arm 40 with the ramp 7 so that the braking mechanism will not be actuated. A failure to bring the train to the required speed limit will cause an actuation of the train stop mechanism as before described.
- 15 It may be, however, that while the train is moving from contact rail 8 to contact rail 9, the train which occupies block *c* will have passed into the succeeding block permitting the relay 2 to again be energized and cause the armature 12 to close the circuit to the contact rail 9. When the train or car therefore reaches contact rail 9, the coil 48 of the speed limit device will be energized and will position the arm 43 to the correct speed for that block, as for example, twenty-five miles per hour as previously described. The cab indicator will inform the engineer of this fact and the train may proceed at a speed of twenty-five miles per hour.
- 20 It will be seen from the foregoing description that the system provides a control for the train both when traffic conditions are clear, as well as dangerous, and the speed limit of the train may be changed at any position along the trackway by the interposing of a set of contact rails and ramps such as has been described. In some instances, it will not be necessary to connect these contact rails so that they will be under the control of the track relay or other parts depending upon the traffic conditions, but the contact rails may be continually energized by a current of definite strength to cause the actuation of the speed limit device to set the speed limit of the train for a speed corresponding thereto, as where there is a bad curve in the trackway. It will also be seen that the particular form of track circuit disclosed and the system of contact rails and ramps may be modified for different types of track systems, and it is intended that the particular system of track circuit control described is illustrative and not limiting upon the scope of the invention.
- 25 Other modifications of the invention will be apparent to one skilled in the art and it is intended that such modifications will come within the invention as are covered by the claims appended hereto.
- 30 I claim:
1. In combination, a railway vehicle, vehicle controlling means thereon, speed-controlled means on the vehicle for controlling said vehicle controlling means, and means spaced along the trackway for setting said

speed-controlled means for a maximum speed limit and for thereafter causing it to operate said vehicle controlling means if the speed of the vehicle is not reduced to within the speed limit for which the speed-controlled means has been set.

2. In combination, a railway vehicle, vehicle controlling means thereon, speed-controlled means on the vehicle for controlling said vehicle controlling means, means along the trackway for setting said speed-controlled means for any of a plurality of different speed limits, and a second means along the trackway spaced from said first named means for causing said speed-controlled means to operate said vehicle controlling means if the speed of the vehicle is not reduced to within the speed limit for which the speed-controlled means has been set before the vehicle passes over said second named means along the trackway.

3. In combination, a railway vehicle, vehicle controlling means thereon, speed-controlled means for controlling said vehicle controlling means, means spaced along the trackway with which said speed-controlled means is adapted to co-act, co-action of said speed-controlled means with the first of said means along the trackway setting said speed-controlled means for a determined speed limit, said speed-controlled means when thus set causing the actuation of the vehicle controlling means upon passing the second of said means along the trackway only when said train passes the second named means along the trackway at a speed greater than the speed for which said speed-controlled means has been set.

4. In combination, a railway vehicle, vehicle controlling means thereon, means spaced along the trackway and speed-controlled means carried by said vehicle and controlled by said means along the trackway for causing the operation of said vehicle controlling means if the speed of said vehicle is not reduced to a determined speed after passing the first of said means along the trackway and before it passes the last of said means along the trackway.

5. In combination, a railway vehicle, vehicle controlling means thereon, two devices spaced along the trackway controlled at least in part by traffic conditions, and means on the vehicle including a speed-controlled device adapted to co-act with said devices along the trackway for causing the train controlling means to act if the speed of the vehicle in passing from one to the other of said devices along the trackway is not reduced to a determined speed when traffic conditions are dangerous.

6. In combination, a railway vehicle, vehicle controlling means thereon, two devices along the trackway, speed-controlled means on the vehicle for controlling said vehicle

- controlling means, and means coöperating with said devices along the trackway for causing said speed-controlled means to actuate said vehicle controlling means if the speed of the vehicle is not reduced to a determined speed limit before it passes the second of said devices along the trackway under one condition of traffic or to a different speed limit under a different condition of traffic. 10
7. In combination, a railway vehicle, vehicle controlling means thereon, two devices spaced along the trackway controlled at least in part by traffic conditions, and means on the vehicle including a speed-controlled device adapted to co-act with said devices along the trackway for causing the train controlled means to act if the speed of the vehicle in passing from one to another of said devices is not reduced to a determined speed under one condition of traffic or to a different speed limit under a different condition of traffic. 15
8. In combination, a railway vehicle, vehicle controlling means thereon, means on the vehicle for controlling said vehicle controlling means comprising a speed-controlled means and a speed limit device capable of being set for any one of a plurality of speeds, means spaced along the trackway for setting said speed limit device for a determined speed, and other means along the trackway for operating said speed limit device. 20
9. In combination, a railway vehicle, electrically-operated vehicle controlling means thereon, a circuit for controlling said vehicle controlling means and coöperating circuit controllers for said circuit, means controlled by the speed of the vehicle connected to one of said circuit controllers, and means connected to the other of said circuit controllers for determining the speed at which the vehicle may run. 25
10. In combination, a vehicle, electrically-operated vehicle controlling means thereon, a circuit for controlling said vehicle controlling means, circuit controllers in said circuit, a speed governor on said vehicle for operating one of said circuit controllers, and a device on said vehicle for determining the speed at which the vehicle may run, for operating the other of said circuit controllers. 30
11. In combination, a railway vehicle, vehicle controlling means thereon, means for controlling said vehicle controlling means comprising a speed-controlled part and a speed limit device positioned upon said vehicle, means along the trackway for setting said speed limit device for any one of a plurality of different speeds, and other means 35
- along the trackway for actuating said speed limit device to cause the operation of the train controlling means if the speed of the vehicle is not reduced to the speed limit for which the speed limit device has been set before the vehicle passes over said last named means along the trackway. 65
12. In combination, a railway vehicle, electrically-operated vehicle controlling means thereon, a circuit for controlling said vehicle controlling means, a speed-controlled circuit controller in said circuit, a second circuit controller coöperating with said first named circuit controller, means normally holding said second named circuit controller in a set position, ramps spaced along the trackway for momentarily releasing said second named controller, a member for controlling the movement of said second named circuit controller when released, an electrical translating device having a part whose movement is proportional to the strength of current passing therethrough connected to said member, means on the vehicle normally holding said member in a set position, means along the trackway for releasing said member and momentarily energizing said electrical translating device, and other means along the trackway for simultaneously releasing said second named circuit controller and said member and for also momentarily energizing said electrical translating device. 70
13. In combination, a railway vehicle, vehicle controlling means thereon, an electrical speed indicator on said vehicle having a pointer whose movement is proportional to the strength of current passing therethrough, means for controlling said vehicle controlling means comprising a part controlled by the speed of the vehicle and a speed limit device, means controlled by said speed limit device for actuating said speed indicator, and means along the trackway for controlling said speed limit device. 75
14. In combination, a railway vehicle, vehicle controlling means thereon, a speed indicator on said vehicle, speed controlled means on said vehicle, and means along the trackway defining a definite space interval coöperating with said speed controlled means to set said speed controlled means for a determined speed and to set the speed indicator for a corresponding speed and for thereafter actuating said vehicle controlling means if the speed of the vehicle is not reduced to within the speed limit set, within the definite space interval. 80
- In witness whereof I subscribe my signature.

FRANK E. BUTTON.
